UNITED STATES PATENT OFFICE.

GUSTAVE M. NELL, OF DENVER, COLORADO, ASSIGNOR TO THE DENVER ROCK DRILL
MANUFACTURING COMPANY, OF DENVER, COLORADO, A CORPORATION OF DELA-
WARE.
MOUNTING FOR ROCK DRILLS.

Application filed March 18, 1921. Serial No. 453,294.

To all whom it may concern:

Be it known that I, GUSTAVE M. NELL, a citizen of the United States, residing at Denver, in the county of Denver and State 5 of Colorado, have invented certain new and useful Improvements in Mountings for Rock Drills, of which the following is a specification.

The present invention relates to means for 10 mounting hand-directed drills and the like on a mechanically adjusted support, and is more particularly directed to improvements in supports for so-called "hand sinkers" so that they may be successfully utilized for 15 drifting.

One of the objects of the present invention is to provide a structure of this character, by which drills having differently arranged handles may be mounted thereon.

20 Another object is to provide a simple and effective clamping or gripping means for securing the drill bit in place.

In the accompanying drawings:—

Figure 1 is a plan view of one embodiment of the invention.

Figure 2 is a side elevation of the same, partly in section showing a drill in place,

Figure 3 is a cross sectional view taken on the line 3—3 of Figure 2,

30 Figure 4 is a side view of the upper portion of one of the jaws, with the clamping bolt in place,

Figure 5 is a similar view, with the bolt removed,

35 Figure 6 is a perspective view of the portion of the jaw shown in Figures 4 and 5,

Figure 7 is a perspective view of the portion of the bolt that engages said jaw,

Figure 8 is a plan view of the rear portion 40 of the mounting showing an adapter in place thereon,

Figure 9 is a longitudinal sectional view therethrough,

Figure 10 is a perspective view of the 45 adapter.

In the embodiment disclosed, the usual guide shell is designated 11, and slidably mounted thereon is a carriage 12 that is moved through the medium of a screw 13 extending longitudinally in the shell, and having a threaded engagement 14 with the carriage. The rear end of the screw is provided with the usual crank handle 15.

The carriage has contiguous to its front end upstanding lugs 16, the upper portions 55 of which, 17, are divergently curved to provide seats for the body 18 of a "hand sinker" or other drilling machine. Jaws 19 have bifurcated lower ends 20 that straddle the lugs and are pivoted thereto, as illustrated at 21. These jaws have inwardly extending projections 22 adapted to bear upon opposite portions of the upper side of the drill body. The jaws terminate in upstanding ears 23 and 23^a, and in the ear 23^a 60 is slidably and rotatably mounted a tie bolt 24 having a nut 25 adjustably threaded on its outer end. A coiled spring 26 on the bolt is interposed between the nut 25 and the ear 23^a, in which said bolt is slidably and 65 rotatably mounted. The ear 23 of the opposing jaw is shown in detail in Figures 4, 5 and 6, and as there illustrated is provided with a transversely elongated opening 27. The head 28 of the tie bolt 24 is correspondingly elongated and is thus adapted to pass through the opening 27 when properly aligned therewith and when turned at right angles the head will extend across the opening and bear against the outer side of the 70 ear, as illustrated in Figure 4. This position is determined by stop shoulders 29 formed on said ear.

With this construction, it will be evident that the jaws may be disconnected by disengaging the tie bolt 24 from the ear 23, and said jaws can thus swing outwardly to permit the placing of a drill upon the carriage. When so placed the jaws are swung to the position illustrated in Figure 3, and the head 28 of the bolt 24 is passed through the opening 27. It is then only necessary to turn the nut 25 in the proper direction, for upon its rotation the bolt 24 will also be initially turned until the head 28 strikes 80 the abutments 29, and continued rotation of the nut causes it to be screwed toward the ear 23^a, thereby compressing the spring 26, and causing the jaws to yieldingly grip upon the drill body, thereby effectively 85 clamping it. A reverse operation of the nut serves to disconnect the jaws.

The rear end of the carriage 12 is provided with spaced upstanding abutment lugs 90 having recessed seats 31 in their front edges, said seats being adapted to receive 105

the usual handle 34 on the rear end of the drill 22^a. Between the rear portions of the lugs 30 is located a transverse ear 35, in which is slidably mounted the shank 36 of a retaining hook 37 that is adapted to embrace the handle, as illustrated in Figure 2. The stem 36 of the hook 37 projects beyond the ear 35 and has threaded thereon a tension nut 38 that bears against a coiled spring 39 surrounding the shank and bearing against the rear end of the ear 35. Thus the rear end of the drill is detachably but effectively secured to the carriage.

In the structure shown in Figure 2 it will be noted that the handle 34 is offset from the longitudinal center of the drill and as is well known to those skilled in the art, this is the usual arrangement where water tubes are employed as it gives access to the mounting for said tubes at the rear end of the drill body and permits their removal and replacement. Where water tubes are not used, it is the practice to place the handles in intersecting relation to the longitudinal center of the drill. It will be obvious that a drill having a handle so placed will not be engaged by the handle retaining means shown in Figures 1 and 2. For such drills an adapter is employed that is illustrated more particularly in Figures 7, 8, 9 and 10. This adapter consists of a body 40 having upstanding forwardly curved abutment lugs 41 adapted to receive the "straight" handle 42 of the drill. This body 35 is also provided with rearwardly extending curved knobs 43 that are received in the seats 31 of the abutments 30. The body 40 is furthermore provided with a central opening 44, through which the shank 45 of a handle-engaging hook 46 passes, the hook 46 cooperating with the lugs 41 to snugly embrace and clamp the handle 42. A nut 47, threaded on the rearwardly projecting end of the shank 45, bears against a coiled spring 48 that is abutted against the ear 35 of the carriage. It will thus be clear that the structure is adapted to successfully maintain in place different drills having differently disposed handles.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In a mounting for rock drills, the combination with a drill holding carriage, of a drill body embracing retaining jaws pivoted

thereto, and means for drawing said jaws toward each other to grip a drill body placed therebetween.

2. In a mounting for rock drills, the combination with a drill holding carriage, of a drill body embracing retaining jaws pivoted at their lower ends thereto, a bolt connecting the upper ends of the jaws, a nut adjustably threaded on the bolt, and a spring interposed between the nut and one of the jaws.

3. In a mounting for rock drills, the combination with a drill holding carriage, of a drill body embracing retaining jaws pivoted at their lower ends thereto, a bolt slidably mounted in one of the jaws and adapted to detachably engage the other jaw, a nut adjustably threaded on the bolt, and a spring interposed between the nut and the jaw in which the bolt is slidably mounted.

4. In a mounting for rock drills, the combination with a drill holding carriage, of relatively movable drill body clamping devices mounted thereon, a connecting member slidable on one device and adapted to detachably interlock with the other device, and means for rotating the member to cause it to interlock with said device.

5. In a mounting for rock drills, the combination with a drill holding carriage, of relatively movable drill body clamping devices mounted thereon, a connecting member slidable on one device and adapted to detachably interlock with the other device, an actuating element rotatable on the member, and means for causing the element to effect a limited rotation of the member and secure a clamping action of the devices.

6. In a mounting for rock drills, the combination with a drill holding carriage, of relatively movable clamping jaws thereon, a bolt slidably and rotatably mounted on one jaw and adapted to interlock with the other on its rotary movement, and a nut adjustably mounted on the bolt for effecting its rotation and also its longitudinal movement.

7. In a mounting for rock drills, the combination with a drill holding carriage, of relatively movable clamping jaws thereon, a bolt slidably and rotatably mounted on one jaw and having an elongated head, the other jaw having an elongated opening that permits the passage of the head when the latter is in one position and prohibits its passage when in a different position, and a nut adjustably mounted on the bolt for effecting its rotation and also its longitudinal movement.

8. In a mounting for rock drills, the combination with a drill holding carriage, of relatively movable clamping jaws thereon, a bolt slidably and rotatably mounted on one jaw and having an elongated head, the other jaw having an elongated opening that permits the passage of the head when the latter

is in one position and prohibits its passage when in a different position, stops on the latter jaw for limiting the rotation of the head, a nut adjustably threaded on the bolt, and a spring interposed between the nut and the jaw in which the bolt is slidably and rotatably mounted.

9. In a mounting for rock drills, the combination with a drill holding carriage having a rear abutment for the handle of a drill, of a handle-engaging retaining hook slidably mounted on the carriage, a tension nut adjustable on the hook, and a spring interposed between the nut and the carriage.
10. In a mounting for rock drills, the combination with a drill holding carriage, of a plurality of abutment members having similarly facing differently shaped seats against which the corresponding sides of 20 differently shaped rock drill handles are respectively adapted to bear.

11. In a mounting for rock drills, the combination with a drill holding carriage, of a plurality of abutment members having 25 similarly facing differently shaped seats against which the corresponding sides of differently shaped rock drill handles are respectively adapted to bear, one of said members normally bearing against the seat of the 30 other and being removable from such seat.

12. In a mounting for rock drills, the combination with a drill holding carriage having a support on which the bodies of rock drills are adapted to rest, of an abutment 35 against which the handles of certain drills are adapted to bear, an adapter block arranged to engage said abutment and having

an abutment against which the handles of other drills are adapted to bear, and means for securing the drills to the carriage.

13. In a mounting for rock drills, the combination with a drill holding carriage having a support on which the bodies of rock drills are adapted to rest, of an abutment 40 against which the handles of certain drills are adapted to bear, a hook bolt holder in rear of the abutment, an adapter block arranged to bear against the abutment and having an abutment for the handle of a rock drill, and a handle-engaging hook bolt 45 slidably mounted in the adapter and in the said holder.

14. In a mounting for rock drills, the combination with a drill holding carriage having upstanding bearing lugs for engagement 50 with a drill body, and clamping jaws pivoted to said lugs.

15. In a mounting for rock drills, the combination with a drill holding carriage having upstanding bearing lugs provided with 55 divergent seats on which a drill body is adapted to rest, clamping jaws pivoted at their lower ends to the lugs and having overhanging portions adapted to bear upon such drill body, and means connecting the 60 upper ends of the jaws for drawing them towards each other.

In testimony whereof, I affix my signature in the presence of two witnesses.

GUSTAVE M. NELL.
